Inventor:

Franz C. Heiser.

FRANCIS C. HEISER, OF BROOKLYN, E. D., NEW YORK.

Design No. 3,277, dated December 8, 1868.

DESIGN FOR A SNUFF-BOX

The Schedule referred to in these Letters Patent and making part of the same.

To all whom it may concern:

Be it known that I, FRANCIS C. HEISER, of Brooklyn, E. D., Kings county, New York, have invented a new and original Design for Snuff-Box; and I do hereby declare that the following is a full, clear, and exact description thereof, which will enable others skilled in the art to make and use the same, reference being had to the accompanying drawing, forming a part of this specification.

The drawing represents a perspective view of my new and original design for snuff-box.

This invention relates to a new and original design for a snuff-box, and consists of a box, A, which is made of sheet-metal or other suitable material, and which is made in form of a gaiter-shoe, as shown. The box can be closed by means of a hinged folding lid, B,

which is so shaped as to fit the upper opening of the shoe. It is held closed by means of a suitable spring-catch, or by equivalent devices. The lid may be ornamented by a star, *a*, or otherwise. On the shoe-box are shown the seams *b b* and the buttons *c c*, or the elastics, *e e*, and the heel *d*, all as on real shoes. When nicely polished, this will be a very beautiful snuff-box, and one which is convenient to carry.

Having thus described my invention,

I claim as new, and desire to secure by Letters Patent—

The design for a snuff-box herein set forth.

FRANCIS C. HEISER.
